CATAMENIAL DEVICE

Earle C. Haas, Denver, Colo.

Application June 2, 1934, Serial No. 728,775

3 Claims. (Cl. 128—263)

This invention relates to a catamenial device and to means for manufacturing, packing and using the same. It relates more particularly to a catamenial device of the type illustrated in applicant's Patent No. 1,926,900 and copending application, Serial No. 672,145 now Patent No. 1,964,911, of which this application is a continuation in part.

The principal object of the invention is to provide a catamenial device of this character which will have a maximum of expansion when in use; a minimum of size when not in use; which will insure the removal of all of the fibers of the catamenial core when withdrawn; and which will straighten and elongate itself to a minimum diameter during withdrawal.

Another object of the invention is to provide an easily disposable and efficient means for packing and protecting the catamenial core until ready for use which will also serve as an applicator for inserting the core in the vagina.

Another object of the invention is to provide efficient means for forming a piece of absorbent cotton into a small, compact self-sustaining core.

A further object is to provide a catamenial absorbent device of the insertion type which will prevent any harsh or sharp edges from contacting the tissues.

Other objects and advantages reside in the detail construction of the invention, which is designed for simplicity, economy and efficiency. These will become more apparent from the following description.

In the following detailed description of the invention reference is had to the accompanying drawing which forms a part hereof. Like numerals refer to like parts in all views of the drawing and throughout the description.

In the drawing:—

Fig. 1 illustrates an absorbent strip as employed in the manufacture of the device.

Fig. 2 illustrates the strip of Fig. 1 as it appears in the finished compressed condition or core, ready for insertion in the applicator.

Fig. 3 illustrates the core in place in an applicator ready for use.

Fig. 4 is a longitudinal section through the applicator of Fig. 3.

Fig. 5 illustrates the core in place in an alternate form of applicator.

Fig. 6 is a diagrammatic view illustrating the mechanism employed for compressing the strip of Fig. 1 to the core of Fig. 2.

As described in the said patent and copending application, catamenial devices of this character

are designed to eliminate all external pads, belts, etc., and are employed internally in the vagina. Such devices comprise an absorbent member to be placed in the vagina with a depending, flexible withdrawing member by means of which the absorbent member may be withdrawn.

Heretofore such devices have been objectionable due to the fact that they were unsanitary; inconvenient and disagreeable to insert; difficult to withdraw when filled with absorbed fluids; and liable to separate in the vagina so as to leave fibers or a portion of the pad remaining therein. The device described in the following specification produces an article, which avoids all these objectionable features.

Commercial absorbent cotton is furnished in rolled strips of uniform width. Owing to the process of manufacture, the cotton fibers in the strip extend in a general longitudinal direction so that the strip has relatively more tensile strength in a longitudinal than in a lateral direction. This parallelity of fibers is utilized in attaining some of the objects of this invention.

A strip of the above type of absorbent cotton is cut laterally so as to provide absorbent strips, such as indicated at 10, of a length equaling the former width of the original strip from which the strips 10 are cut. In the strips 10 the fibers naturally extend laterally so that the strips could be easily pulled apart in a longitudinal direction, but would resist pulling apart in a lateral direction. To increase the longitudinal strength of the strip, a thread is stitched as indicated at 11 throughout the length thereof. This thread firmly ties all of the lateral fibers together and produces a strip which resists separation both laterally and longitudinally. It is preferred to stitch this thread 11 with a chain stitch, such as employed for closing flour sacks and the like, and to continue the stitching beyond the extremity of the strip 10 to form a flexible, chain-stitched withdrawing member 12.

The next step in the manufacture of the device is to force the strip 10 into a die and compress it under high pressure from both the sides and the ends to form a hard, cylindrical core 13 with the withdrawing member 12 extending therefrom. The natural result of compressing the strip is to convolute it upon itself so that the seam 11 might assume a position in the core 13 as indicated in broken line in Fig. 3. The die with which the core 13 is pressed preferably does not extend to the extreme end of the core. This allows a mushroom-like end 14 to form. The end 15

14 is of greater diameter and of less density than the remainder of the core.

The compressed core 13 is then loosely slipped into the extremity of a cardboard tube with the withdrawing member 12 extending therethrough, and with the mushroom-like extremity 14 covering, protecting and extending beyond one extremity of the tube.

A typical die for accomplishing the compressing operation is indicated diagrammatically in Fig. 6. Such a die would consist of a female block 17, in one side of which a receiving groove 18 is formed with a concave, semi-cylindrical, side wall 19. A side compressing plunger 20 moves into the groove 18. The face of the plunger 20 contains a semi-cylindrical concavity 21. A plunger 22 is positioned above the die 17 so as to enter the cylindrical opening between the side wall 18 and the concavity 21.

In use, the strip of Fig. 1 is forced into the receiving opening 18. The plunger 21 is then moved inwardly to force the strip to a cylindrical form or core and impart the initial side compression. The plunger 22 then descends to impart the final end compression. A space 23 is left about the bottom of the die to allow the mushroom extremity 14 to expand therein. A groove 24 accommodates the withdrawing member 12.

The cardboard tubes form applicators for inserting the cores in the vagina. They may be used as a double tube, such as shown in Fig. 3, or as a single tube, such as shown in Fig. 5. The double tube comprises an outer tube 15 in which an inner tube 16 is telescopically fitted. The core 13 is inserted in the extremity of the tube 15 as shown in Fig. 4 with the inner tube 16 inserted therebehind. The outer tube 15 may be employed alone without the inner tube 16 as shown in Fig. 5, if desired. It will be noted that the tube 15 not only forms an applicator, but also a convenient method of packing, marketing and protecting the individual cores.

The device is used by inserting the tube 15 in the vagina and, if the inner tube 16 is employed, then pressing upon the inner tube to cause it to telescopically pass into the outer tube and force the core therefrom into the vagina leaving the withdrawing member 12 depending therefrom. If the outer tube only is employed, the mushroom-like extremity 14, which protects the walls of the vagina from injurious contacts with the end of the tube during the insertion operation, engages the vagina walls to maintain the core in place as the tube 15 is withdrawn.

It is desired to call attention to the fact that the tubes, being made of cardboard, will quickly soften and disintegrate in water so that they may be discarded in a toilet bowl and flushed away. The natural moisture of the secretions present in the vagina causes the core to expand from its highly compressed condition as the fluids are absorbed.

When it is desired to remove the core, the withdrawing member 12 is drawn upon. This, owing to the convolutions of the strip, causes the strip to straighten and be withdrawn in the elongated uncompressed condition of Fig. 1. This facilitates the withdrawing operation and reduces the possibility of the absorbed fluids being pressed from the absorbent.

The tube 15 allows the core to be conveniently inserted; the end 14 prevents any injury; the straightening convolutions allow easy withdrawal; and the laterally extending fibers, in combination with the longitudinal tie member or seam 11, bind the entire structure so that all possibility of leaving portions or fibers in the vagina is avoided. Thus all of the objects of the invention are accomplished.

The entire assembly of core and tube is sterilized and wrapped in cellophane or a similar protective enclosure, and is ready for the market. The strip or core need never be touched with the hands.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:—

1. A combined container and applicator for a catamenial device of the type consisting of a compressed cylindrical core of absorbent material, comprising: a first cardboard tube of a diameter to snugly receive said core and containing the latter; a second cardboard tube contained within the first tube with its first extremity in contact with said core and with its other extremity projecting from said first tube so that when said latter extremity is forced within said first tube, said first extremity will force said core from said first tube.

2. A combined container and applicator for a catamenial device of the type consisting of a compressed cylindrical core of absorbent material, comprising: a first cardboard tube of a diameter to snugly receive said core and containing the latter; a second cardboard tube contained within the first tube with its first extremity in contact with said core and with its other extremity projecting from said first tube so that when said latter extremity is forced within said first tube, said first extremity will force said core from said first tube, said second tube being of a diameter to frictionally engage the interior wall of the first tube to hold said tubes together.

3. A combined container and applicator for a catamenial device of the type consisting of a compressed cylindrical core of absorbent material, comprising: a first cardboard tube of a diameter to snugly receive said core and containing the latter; a second cardboard tube contained within the first tube with its first extremity in contact with said core and with its other extremity projecting from said first tube so that when said latter extremity is forced within said first tube, said first extremity will force said core from said first tube, said second tube being of a diameter to frictionally engage the interior wall of the first tube to hold said tubes together, said tubes being substantially equal in length so that said second tube will project from said first tube the length of said core when the latter is in place therein and will pass completely through said first tube when said core is expelled therefrom so that there will be no projection of said second tube after the expelling operation.

EARLE C. HAAS.
